In Germany September 22, 1936

4 Claims. (Cl. 200—116)

My invention relates to thermostatically actuated automatic switches, principally for opening an electric circuit in case of overload or short circuit.

For thermostatically releasing automatic switches, aside from making use of heated wires or heated rods which change their length when heated, bimetallic strips are mostly used which bend or buckle, as the case may be, when the given excess current heats these strips either directly or indirectly above a given temperature. This motion of the bimetallic strip is utilized for releasing the switch mechanism. Most of the arrangements of this type known in the prior art are of complicated construction, especially in the switch mechanism, and require a comparatively large amount of space. In some cases, the designer is limited to the use of quick-acting switch mechanisms, because only this type of mechanism produces the high opening speed necessary for interrupting currents incident to heavy loads or to short circuits.

In electric installations which are operated at a very low voltage, for instance such as operate within about forty volts, also very heavy currents are likely to occur, but in these installations the danger of arc formations during the interruption does not exist to such an extent as for instance in higher voltage installations. While in such low voltage installations the possibility exists to construct the automatic switch in a simpler form, the prior art has in such cases almost exclusively resorted to fuses which are renewed after they have once responded.

It is undesirable, however, in electric installations which are used for instance in automobiles, aircraft, radio installations, or for similar purposes, and which are operated within the low voltage range above-mentioned, to be compelled, after the fuse has responded, to exchange the burnt-out fuse with a new one. This might be dangerous for instance in aircraft, in case an important circuit is opened in this manner, because of the long time which it takes to make this change.

The present invention therefore proposes to employ for such purposes a thermostatically operating automatic switch, which, however, with the necessary change in design, may also be used for interrupting circuits operated at higher voltages.

In the design for automatic cut-out switches to be used in low voltage plants, it is necessary that the switch be constructed so that it occupies a very small space and weight, but that it never-

theless should be capable of fully safeguarding the circuit in which it is placed. It is necessary above all that with the use of a thermostat as a releasing element, the opening of the contacts occurs quickly, which is particularly important in case of a short circuit. The present invention solves this problem in a simple manner by fixing one end of the spring which carries one contact, and one end of the strip-shaped bimetallic spring which carries the second contact in two different planes spaced a considerable distance apart. The two springs may extend either parallel to or at an angle toward one another. At the normal closing of the switch, the free ends of these two springs are latched together so that when the bimetallic strip is deformed in its response to an overload, the two springs are distorted first together in the same direction whereby the latch between the two strips is disengaged and the two contact springs fly apart and thus open the circuit. The manner in which this occurs will be described later in detail with reference to the drawings.

The arrangement of such a thermostatically operated automatic switch according to the invention affords a particularly simple and condensed arrangement of the switch elements and therefore fulfills the requirement made when these switches are used for the purposes stated hereinbefore.

It is further necessary in switches of this type that the resetting device, if one is used in the switch, be arranged in such manner that it does not interfere with the free operation of the cut-out mechanism. My invention solves also this problem of a trip-free mechanism in a very simple manner.

My invention is illustrated in the accompanying drawings in which—

Figures 1 and 2; 3, 4 and 5 respectively show two different modifications of the switch involving the novel features according to my invention, all of these figures showing the switch in longitudinal sectional elevation.

Figure 1a shows the spring *i* in Figures 1 and 2 in end elevation.

Figures 6, 7 and 8 illustrate another embodiment in two longitudinal sections representing the contact opening and the contact closing position, and in a front view, respectively.

Figure 9 indicates a modification of the shape and arrangement of the cooperating contact springs; and

Figures 10a, 10b and 11a, 11b show two groups of variants serving for adjusting a switch ac-

cording to the invention to different overload conditions.

Referring to Figures 1, 1a and 2, these figures show the simplest form in which the idea according to my invention may be reduced to practice. Figure 1 shows the switch in closed position, and Figure 2 in open position. In these figures, *a* represents the base plate which may consist of any insulating material suitable for the purpose. On this base plate are mounted, spaced apart by the spacing block *b* of insulating material, the bimetallic strip *c* and the contact spring *d*. The latter is offset at its end towards the strip *c* and carries the contact *f* at its end which cooperates with the contact *e* mounted at the end of bimetallic strip *c*. Contact spring *d* carries further an extension *g* made of insulating material which extends in the direction of the general longitudinal axis of this spring and which carries at its end a small latch plate *h*. The end of this latch plate is disposed in the path of a spring *i* fixed at the end of bimetallic strip *c* and provided with a perforation *i'*, shown more clearly in Figure 1a, in which the end of latch plate *h* engages when contact spring *d* and bimetallic strip *c* are latched together and contacts *e* and *f* are closed. The fixed end of strip *c* is connected by way of a conducting strip *j* to binding post *k* of the switch, and the fixed end of contact spring *d* is connected by way of a conducting strip *m* to the other binding post *n* of the switch. A protecting cap *p*, which is held in place by means of a hand-screw, encloses the entire switch mechanism.

This arrangement operates as follows. If an overload condition should arise when the switch is in closed position, as in Figure 1, the bimetallic strip *c* is heated and thereby bends at its free end toward base *a*. Thereby both the strip and contact spring *d* first travel together downwardly, but in doing so, the latching elements *h* and *i* shift in the direction of the longitudinal axis of spring *d* relatively to one another, and when strip *c* has bent down far enough, latch *h* is disengaged from spring *i*, and contact spring *d*, being now free, quickly snaps upwardly due to a normal upward bent provided near its mounting point as shown in Figure 2. The latch mechanism disengages during the downward bending of strip *c* due to the spacing between strip *c* and contact spring *d* provided by insulating block *b*. When the latched contacts, as shown in Figure 1, bend downwardly together, the end of spring *d* where latch *h* is located follows a circular path which is directed toward the side of binding post *n* and thus away from spring *i*, while the free end of spring *i* at the same time follows a circular path which is directed toward binding post *k* and thus away from latch *h*. As soon as the two contact elements have followed a sufficient distance in these two paths, they slide apart and the latch mechanism is opened and the contact arms fly apart. The greater the difference in the radii on which the two contact arms move, the sooner the mechanism will be unlatched. As soon as the bimetallic strip has cooled, it reassumes its straight position shown in Figures 1 and 2, but contact spring *d* remains in its elevated position shown in Figure 2. In order to reclose and relatch the contacts, it is necessary in this modification to loosen the holding screw *o* of casing *p* to remove the casing and to depress spring *d* until latch *h* re-engages spring *i*.

78 The modification shown in Figures 3, 4 and 5

is distinguished from that shown in Figures 1 and 2 by the additional provision of a resetting mechanism which can be operated from outside of the casing but which is constructed so that it does not interfere with the free operation of the automatic cut-out mechanism and so that in case it is accidentally operated in such manner as would cause such interference, the circuit is opened thereby. In this modification, the thermostatic releasing mechanism comprising the spring *d*, bimetallic strip *c*, contacts *e* and *f* and the latch mechanism *h*, *i* are the same and function in the same manner as described with reference to Figures 1 and 2. In this case the bimetallic strip *c* is connected to binding post *n*.¹⁵

The contact spring *d*, separated from strip *c* by means of the insulating block *b*, is connected to binding post *k* by way of auxiliary contacts *s*, *t*. Contact *s* is mounted on a contact spring *r* connected directly to binding post *k*, and contact *t* is mounted at the end of spring *u* which leads to the fixed end of contact spring *d* where it is held together with spring *d* on block *b*. This auxiliary contact, which is normally closed when the automatic switch is closed, is controlled by means of a press button *v* mounted in casing *p*, held by screw *o* to base plate *a*, so that when this button is depressed, contacts *s*, *t* are opened. This button has a downward extension *w* which, when the button is depressed, engages the insulating strip *g* of spring *d*. When the automatic cut-out switch has responded to an overload and has assumed the open position shown in Figure 4, the insulating piece *g* of spring *d* has engaged extension *w* of the press button and thrown the latter upwardly into a position shown in Figure 4. If now the operator attempts to reclose and relatch the switch mechanism by depressing button *v*, contact spring *d* approaches the bimetallic strip *c*, but before the switch contacts *e* and *f* can be closed, the portion *w'* of the contact button carries the auxiliary contact *t* of spring *u* away from contact *s*, so that when the depression of button *v* is continued and switch contacts *e* and *f* are closed and the latch *h* engages spring *i* and locks contacts *e* and *f* together, auxiliary contacts *s* and *t* are still open, and thus the circuit is still open. It can be closed only when button *v* is released so that spring *u* carries auxiliary contact *t* back into contact with *s*. It will be seen from this arrangement that if now with all contacts closed and the switch in operation, as shown in Figure 3, an attempt should be made accidentally to depress button *v*, which would interfere with the free opening of the latched switch, should the circuit condition at that moment call for an opening, auxiliary contacts *s*, *t* will be opened and the circuit will be interrupted thereby.⁴⁵

The modification shown in Figures 6, 7 and 8⁶⁰ is distinguished from the switch forms shown in the previously described figures by the following arrangement. In this case the bimetallic strip *c* with its contact *e* and spring *i* at the free end, is fixed on the casing *p*, which for this purpose may be made of any suitable insulating material. Downwardly spaced from the fixed end of strip *c* is fixed the end of contact spring *d*. Otherwise these elements are shaped and function in the same manner as described with reference to Figures 1 and 2, except that their position is inverted. The binding posts *k* and *n* which are mounted on base plate *a* (see Figure 7) have connected to them latch springs *x*, *x* which cooperate with correspondingly disposed latches⁶⁵

y, y connected respectively with the fixed ends of contact spring *d* and bimetallic strip *c*, as shown in Figures 6 and 7. In this manner spring *d* and strip *c* become connected respectively with the binding posts *n* and *k* when casing *p* is attached to the base plate *a*, as shown in Figure 7, by means of latch springs and latches *x, x, y, y*. The switch is shown in Figure 7 in closed position. If now the switch responds due to an overload, the two switch contacts *e* and *f* become unlatched and fly apart and assume the position shown in Figure 6. When this has occurred and in order to reclose the switch, the operator removes casing *p* from base plate *a*, whereby he automatically disconnects the entire switch from binding posts *k* and *n*. He now can reclose and relatch the contacts *e* and *f* with his finger. Only in relocking cover *p* on base plate *a* by means of latch springs *x, x* can the circuit eventually be closed.

My invention is not limited to the particular constructive details shown in the three modifications. For simplicity sake, for instance only a single pole switch has been shown. It is quite obvious that a number of such switches may be easily mounted side by side, since they are very narrow, as may be seen from Figure 8, and thus any number of poles of a circuit may be accommodated and be automatically interrupted. For instance, four of such automatic switches for four conductors may be accommodated within the compass occupied by prior art automatic switches capable of interrupting only a single line.

Moreover, the construction of the switch according to my invention is not limited to the particular manner of latching the two contact-carrying elements *c* and *d* together. Thus, for instance, the latch plate need not be located on an extension of the contact spring *d* but on an extension of the bimetallic strip *c*. In this case a latch plate is provided at the free end of the bimetallic strip and an angularly bent spring is provided at the free end of the contact spring *d*; in other words, the elements *i* and *h*, for instance in Figures 1 and 2, may be reversed, the spring *i* may be mounted on the insulating piece *g* and the latch *h* may be mounted at the end of bimetallic strip *c*. Also the latching point may be located intermediate the ends of the two contact-carrying elements *c* and *d*, in which case angularly shaped springs may be attached to the free ends of the contact-carrying elements *c* and *d* as latching elements.

A modification combining the foregoing modifications is shown in Figure 9. The bimetallic strip *c* carries an insulating piece *g* to which a latch *h* is secured, the latch and the coacting spring being so shaped that the latching point lies between strip *c* and spring *d*.

Furthermore, referring for instance to Figures 1 and 2, the unlatching may occur earlier or later during the bending process of the bimetallic strip according to the relative position of the latching elements to the points at which the contact-carrying elements *c* and *d* are fixed. For instance if in Figure 1 the latch plate *h* instead of being fixed at the upper side of insulating piece *g* is fixed on its underside, as it is illustrated in Figure 10a, the automatic cut-out will respond earlier at the same load than it would respond with the arrangement shown in Figures 1 and 2. On the other hand, if the latch plate *h* should be raised higher above insulating piece *g*, in other words if the latching point should be ele-

vated high above the contact mechanism, as is illustrated in Figure 10b showing an insulating piece *g* of increased thickness, the contacts would be unlatched very much later. Also, the further the two contact-carrying elements *c* and *d* are removed from one another, in other words the higher spacing block *b*, the quicker the unlatching would occur at the same overload. Thus in the manufacture of the switch, its constituent parts may all be the same, but for different overloads or for different times of response, spacing blocks of different heights may be used in order to determine the desired point of response. Accordingly, the spacing blocks *b, b'* and *b''* in Figures 1, 10a and 10b are distinguished from one another by different heights.

Also the time of response may be varied by increasing or decreasing, as the case may be, the relative lengths of the two contact-carrying elements *c* and *d*. This will either increase or decrease the difference in the radii of the circular paths through which the free ends of these elements move and bring about an earlier or later response of the switch from the time when the overload manifests itself in heating the strip *c*. An example embodying the last-mentioned modification is represented by Figures 11a and 11b. The bimetallic strip *c* and the spring *d* shown in Figure 11a are arranged similarly to Figure 1, except that the spacing block *b* allows exchanging of spring *d* by a shorter spring *d''* as shown in Figure 11b, which effects an earlier response to a given overload.

I claim:

1. A thermostatically released cut-out switch having two switch contacts and a contact spring carrying one of the switch contacts and tending to move its contact into open position, and a thermostatically operable bimetallic strip disposed to control the other switch contact, said spring and said strip element each being fixed at one end and spaced a given distance apart one from and above the other, and means at the free ends of said elements for normally latching them together in contact closing position, whereby due to the relative spacing of said elements a relative motion of the latched ends in axial and opposite directions is produced when the bimetallic strip is thermostatically bent into its own contact opening position against the opening tendency of said contact spring, by which motion the element ends are unlatched and the spring is permitted to move its contact away from said strip into its own open contact position.

2. A thermostatically released cut-out switch having two switch contacts and a contact spring carrying one of the switch contacts and tending to move its contact into open position, and a thermostatically operable bimetallic strip disposed to control the other switch contact, said spring and said strip element each being fixed at one end and spaced a given distance apart one from and above the other in the same plane, a latch spring fixed at the end of said strip and extending substantially at right angles to it and across said contact spring when in closing position, and a latch fixed at the end of said contact spring and arranged to engage said latch spring in contact closing position for normally latching the strip and the contact spring together in contact closing position, whereby due to the relative spacing of said contact spring and said strip a relative motion of the latched ends in opposite directions is produced when the bimetallic strip is thermostatically bent into its own con-

tact opening position against the opening tendency of said contact spring, by which motion the latched ends are unlatched and the contact spring is permitted to move its contact away from said strip into its own open contact position.

3. A thermostatically released cut-out switch having a base plate and two binding posts on said plate, and a casing fitted onto said plate and enclosing said posts, said casing containing two switch contacts and having mounted in its interior a contact spring, carrying one of said switch contacts and tending to move its contact into open position, and a thermostatically operable bimetallic strip disposed to control the other switch contact, said spring and said strip element each being fixed at one end to said casing and spaced a given distance apart one from and above the other in the same plane, and means at the free ends of said elements for normally latching them together in contact closing position, whereby due to the relative spacing of said elements a relative motion of the latched ends in axial and opposite directions is produced when the bimetallic strip is thermostatically bent into its own contact opening position against the opening tendency of said contact spring, by which motion the element ends are unlatched and the spring is permitted to move its contact away from said strip into its own open contact position, and

yielding locking contact elements connected respectively to said binding posts and to the fixed ends of said contact spring and said strip for connecting said spring and said strip respectively to said binding posts and for locking said casing to said base plate.

4. A thermostatically released cut-out switch having a base member, two switch contacts, an overload-responsive bimetallic strip disposed to control one of said contacts, said strip having one end firmly secured to said base, a spring member carrying said other contact, said spring member being spaced apart from and substantially parallel to said strip and having the tendency to move away from said strip, one end of said spring member and the free end of said strip forming a latch connection for holding said strip and said spring member in contact-closing position, said latch connection being designed to permit said spring member to travel along with said strip during a releasing period within which said ends effect a longitudinal displacement relative to each other, and means for exchangeably securing the other end of said spring member to said base, said means being designed to selectively accommodate a different spring member in a different spacial relation to said strip in order to vary said period.

WILHELM SATTLER. 30
